UNITED STATES PATENT OFFICE.

CHARLES J. THATCHER, OF NEW YORK, N. Y.

OXIDATION AND REDUCTION PROCESS AND APPARATUS THEREFOR.

1,397,562.

Specification of Letters Patent.

Patented Nov. 22, 1921.

Application filed January 24, 1920. Serial No. 353,743.

To all whom it may concern:

Be it known that I, CHARLES J. THATCHER, a citizen of the United States, and resident of 27 West 95th St., New York, in the county of New York and State of New York, have invented certain new and useful Improvements in Oxidation and Reduction Processes and Apparatus Therefor, of which the following is a specification.

10 The invention relates to a process and apparatus for electrolytically oxidizing substances, such as anthracene, or for electrolytically reducing compounds of like or similar nature. It may be applied to the oxidation or reduction of compounds which are either solid or liquid and which are either soluble or insoluble in the electrolyte used.

The apparatus for this purpose consists of a plurality of electrolytic cells connected 20 preferably in series or series parallel, and having separated anode and cathode compartments. The cells should preferably be of a type providing for vigorous agitation of the electrolyte and in which the agitation 25 tends to maintain a homogeneous suspension of any suspended substance to be oxidized or reduced, and which might otherwise settle out at the bottom, or float at the top. A suitable cell for this purpose is that 30 described in my copending application for U. S. Letters Patent, Serial No. 332,228.

The accompanying drawings show, diagrammatically, a series of such cells with suitably arranged siphons or tubes connecting the successive anode and cathode compartments.

The apparatus and process will be described as it is adapted to the electrolytic oxidation of anthracene to anthraquinone by 40 a dilute sulfuric acid solution of sodium bichromate. To this end, the cathode compartments of the cells are fed with spent chrome liquors from a preceding oxidation, the dissolved solids of which consist mostly 45 of sodium and chromium sulfates and little, if any, bichromate. If the liquors are those derived from a prior operation of this process, they may contain sulfuric acid of moderate concentration and may still be hot, retaining the heat derived from the electrolytic or the oxidation process.

Such liquors may be stored in a suitable vat, as the vat 1; and from which the liquors are caused to flow to the cathode compartment 55 of the first or near end cell of a series of cells 2 as through a pipe 3. This pipe

may be provided with a suitable valve such as the float valve 4, which admits the spent liquor to the cells only when the level of the liquid therein has fallen below that determined by a constant level siphon 5, which controls the final outlet of the liquor after its passage through the series of cells 2. The catholyte from the first cell is arranged to flow to the cathode compartment of the second, and so on to each succeeding cell in the series, through siphons or over-flow pipes 6.

During their passage through this succession of cathode compartments the spent 70 liquors lose most of the excess sulfuric acid which they contain, and by migration of SO_4^{2-} -ions through the diaphragms into the anode compartments; hydrogen, also, escapes from the cathodes, tending to keep 75 the catholyte suitably stirred. Any sodium bichromate remaining in the spent liquors from the preceding oxidation is reduced to chromium and sodium sulfates during the 80 passage of the catholyte through the series of cathode compartments. It is important that the spent chrome liquors thus fed into the cells should contain an excess of sulfuric acid, and an excess more than sufficient 85 to compensate the aforesaid loss of sulfuric acid from the catholyte by migration. Otherwise, the catholyte becomes neutral or 90 alkaline before reaching the last or far end cell and chromium compounds may precipitate.

The number of cells employed should of course be suitably selected to fit the conditions of operation, such as current-density, rapidity of flow of the liquors, etc. In such a suitably selected number of cells, by the 95 time the catholyte reaches the last cell of the series, it has had all its bichromate reduced to chromium and sodium sulfates and has lost most of its sulfuric acid. In this condition, and at this point, the catholyte is 100 now allowed to flow into the anode compartment of the last cell—that farthest removed in the series from the near end cell into which the catholyte was fed. This transference of the catholyte to the first of the 105 anode compartments may be accomplished in any suitable manner, as by a siphon 7, or by an overflow arrangement or any other suitable means, (not shown).

The anolyte now begins to be oxidized at 110 the anode of the cell, regenerating sodium bichromate. Into this or some suitably ad-

5 jacent anolyte compartment, anthracene is now fed in accordance with the process, as from a tank 8, preferably in the form of a paste of a very finely-divided, sublimed an-
10 thracene mixed up with a little water, or preferably with a little of the catholyte from the last cell from which it has been suitably withdrawn for that purpose. It is advantageous to thus use catholyte, similar-
15 larly to the procedure set forth in an application for U. S. Letters Patent filed by me of even date herewith, because it avoids dilution of the liquors, which since they are used over again, would be cumulative and finally necessitate evaporation to restore the requisite concentration.

With a suitable cell, provided with a heat insulated covering if necessary, and at a suitable current-density, the anolyte at this 20 point will be at a temperature of 75° C. or thereabout. All of the conditions of the anolyte, therefore, closely approximate those now employed in the chemical oxidation of anthracene to anthraquinone, which, as in 25 this anolyte, is started at a temperature of 75° C. or so in a liquid free or substantially free from sodium bichromate and sulfuric acid. In the chemical oxidation, a dilute sulfuric acid solution of sodium bichromate 30 is gradually added, with constant stirring, to a suspension of anthracene in water at 75° C. or so. These, to all intents and purposes, are the conditions obtaining in the anolyte to which the anthracene is added in 35 the practice of this invention, so that it does not depart from the long established conditions found necessary in the manufacture of anthraquinone.

By the electrolytic oxidation, sodium bi- 40 chromate and sulfuric acid begin to be formed now and the primary reaction of oxidizing the anthracene to anthraquinone is induced just as in the chemical oxidation process. Under suitably arranged condi- 45 tions, the oxidation of the anthracene keeps step with the generation of sodium bichromate in the anolyte; so that there is at no time any considerable excess of bichromate or sulfuric acid; excessive oxidation, 50 resulting in formation of carbon dioxide and water, is thus avoided, as contrasted with previous unsuccessful attempts to oxidize anthracene in electrolytic cells.

Both the anthracene and anthraquinone 55 are kept in a homogeneous suspension in the electrolyte by vigorous agitation such as may be provided by a stirrer of the electrolytic cell described in my aforementioned patent application. In this homogeneous 60 condition, the anolyte passes through the second and so on through each successive anode compartment of the series of cells, through suitably disposed over-flow pipes or siphons 9, or by some other proper means. It is 65 advantageous to have the inlet leg of the

siphon short and ending near the upper level of the electrolyte, so that there may be no settling out of the suspended anthracene or anthraquinone during its passage through the said siphons. And it is also 70 advantageous to so select the bore of these siphons that a suitably rapid stream of anolyte will flow through the siphons to insure complete carrying over of suspended solids; or any other suitable means of ac- 75 complishing the same result may be employed.

By the time the anolyte reaches the last of the anode compartments, the anthracene is all or substantially all oxidized to anthra- 80 quinone, the temperature conditions being so controlled that the last cell of the series approximates a temperature of 95° C. It should require ten (10) hours or more for the suspended anthracene to pass through 85 the series of anode compartments during its oxidation. From the last of this series of compartments the anolyte, bearing the suspended solids, flows through the over- 90 flow siphon 5, the height of the opening of which determines the level of the entire series of electrolytes. The rate of flow through the cells can be controlled by a cock 10 at any suitable point, e. g. in the siphon connecting the anolyte and catholyte. 95

The mixture flowing through the over- 100 flow siphon may be collected if necessary in a vat 11 provided with a heating coil 12 or other heating means and with a stirrer 13, as shown, to complete the oxidation of 10 the anthracene to any suitable degree. From the latter vat, the anthraquinone in suspension flows out to a filter or other means (not shown) for separating the anthraquinone which is to be dried, and the 10 filtrate is returned to the vat 1 for a further cycle of operations.

I claim:

1. The process of electrolytic oxidation or reduction, which consists in inducing a 11 flow of spent electrolyte, exposing the electrolyte in the first direction of flow to electrolytic action opposed to the primary reaction, and in the reverse direction of flow to electrolytic action inducing the primary 11 reaction, introducing the substance to be converted by the primary reaction at substantially the most inert condition of the electrolyte, collecting the electrolyte and said substance, and separating the latter from the 12 former.

2. The process of electrolytic oxidation or reduction, which consists in inducing a 12 flow of spent electrolyte, exposing the electrolyte in the first direction of flow to electrolytic action opposed to the primary reaction, and in the reverse direction of flow to electrolytic action inducing the primary reaction, introducing the substance to be converted by the primary reaction at substan- 13

tially the most inert condition of the electrolyte, collecting the electrolyte and said substance, separating the latter from the former, and returning the spent electrolyte 5 for a further cycle.

3. The process of manufacturing anthraquinone by electrolytic oxidation of anthracene, which consists in inducing a flow of a electrolyte comprising an acid-reacting

10 aqueous solution containing chromium compounds capable of being electrolytically oxidized to bichromate ions, exposing the electrolyte in the first direction of flow to electrolytic reducing action, and in the re-

15 verse direction of flow to electrolytic oxidizing action, introducing anthracene substantially at the point of reversal, causing anthracene and the anthraquinone formed to be carried along by said electrolyte and con-

20 tinuing the electrolysis until substantially all of the anthracene is oxidized to anthraquinone, collecting the electrolyte, and separating the anthraquinone therefrom.

4. The process of manufacturing anthra-

25 quinone by electrolytic oxidation of anthracene, which consists in inducing a flow of an electrolyte composed of acid-reacting aqueous solution containing chromium compounds capable of being electrolytically oxidized to

30 bichromate ions, exposing the electrolyte in the first direction of flow to electrolytic reducing action, and in the reverse direction of flow to electrolytic oxidizing action, introducing anthracene suspended in a por-

35 tion of reduced electrolyte substantially at the point of reversal, causing anthracene and the anthraquinone formed to be carried along by said electrolyte and continuing the electrolysis until substantially all of the

40 anthracene is oxidized to anthraquinone, collecting the electrolyte, and separating the anthraquinone therefrom.

5. Electrolytic oxidation or reduction ap-

45 paratus, comprising: a series of electrolytic cells with separated anode and cathode compartments; means to feed electrolyte to a compartment of an end cell; connections between the successive compartments of like polarity to permit the electrolyte to flow

50 through the series in one direction; means to maintain the liquid level within the cells; a connection between the cathode and anode compartments of the far end cell; and communications between the successive compartments

55 of polarity opposite to said first series to permit the electrolyte to flow in a direction reverse to its initial flow through the compartments.

6. Electrolytic oxidation or reduction ap-

60 paratus, comprising: a series of electrolytic cells with separated anode and cathode compartments; means to feed electrolyte to a compartment of an end cell; connections between the successive compartments to per-

65 mit the electrolyte to flow through the series

in one direction; means to maintain the liquid level within the cell; a connection between the cathode and anode compartments of the far end cell; communications between the successive compartments of like polarity 70 to permit the electrolyte to flow in a direction reverse to its initial flow through the compartments; and means to control the flow.

7. Electrolytic oxidation or reduction ap-
paratus, comprising: a series of electrolytic 75 cells with separated anode and cathode compartments; means to feed electrolyte to a compartment of an end cell; connections between the successive compartments to permit the electrolyte to flow through the series 80 in one direction; means to maintain the liquid level within the cells; a connection between the cathode and anode compartments of the far end cell; communications between the successive compartments of like polarity 85 to permit the electrolyte to flow in a direction reverse to its initial flow through the compartments; and means to admit to one of the compartments of the far end cell the material to be reacted upon. 90

8. Electrolytic oxidation or reduction ap-
paratus, comprising: a series of electrolytic 95 cells with separated anode and cathode compartments; means to feed electrolyte to a compartment of an end cell; connections between the successive compartments to permit the electrolyte to flow through the series 100 in one direction; means to control the supply of electrolyte to maintain the liquid level within the cells; a connection between the cathode and anode compartments of the far end cell; communications between the successive compartments of like polarity to permit the electrolyte to flow in a direction 105 reverse to its initial flow through the compartments; and an outlet connection from a compartment of the near end cell adapted to determine the electrolyte level.

9. Electrolytic oxidation or reduction ap-

110 paratus, comprising: a series of electrolytic cells with separated anode and cathode compartments; means to feed electrolyte to a compartment of an end cell; connections between the successive compartments to permit the electrolyte to flow through the series 115 in one direction; means to control the supply of electrolyte to maintain the liquid level within the cells; a connection between the cathode and anode compartments of the far end cell; communications between the suc-

120 ccessive compartments of like polarity to permit the electrolyte to flow in a direction reverse to its initial flow through the compartments; an outlet connection from a compartment of the near end cell adapted to determine the electrolyte level, and a tank to receive the flow therefrom and provided with suitable stirring apparatus.

10. Electrolytic oxidation or reduction ap-

130 paratus, comprising: a series of electrolytic

cells with separated anode and cathode compartments; a supply tank to feed electrolyte to a compartment of an end cell; connections between the successive compartments to permit the electrolyte to flow through the series in one direction; a float valve to control the supply from said supply tank to maintain the liquid level within the cells; a connection between the anode and cathode compartments of the far end cell; communications between the successive compartments of like polarity to permit the electrolyte to flow in a direction reverse to its initial flow through the compartments; means to control the flow; means to admit to a compartment of the far end cells the material to be reacted upon; an outlet connection from a compartment of the near cell adapted to determine the electrolyte level; and a suitable tank to receive the flow therefrom, and stir-

ring apparatus for stirring the electrolyte delivered thereto.

11. The process of electrolytic oxidation or reduction, which consists in inducing a flow of spent electrolyte, exposing the electrolyte in the first direction of flow to electrolytic action opposed to the primary reaction, and in the reverse direction of flow to electrolytic action inducing the primary reaction, causing the substance to be converted by the primary reaction to enter into the electrolyte in which the primary reaction occurs, collecting the electrolyte and said substance, and separating the latter from the former.

Signed at New York, in the county of New York and State of New York, this 23rd day of January, A. D. 1920.

CHARLES J. THATCHER.
